INVENTOR

BY Victor J. Evans

ATTORNEY

J. L. Wright

WITNESS:

UNITED STATES PATENT OFFICE.

OSCAR ARNOLD, OF WOODRIDGE, NEW JERSEY.

CARD HOLDER.

Application filed May 11, 1923. Serial No. 638,337.

To all whom it may concern:

Be it known that I, OSCAR ARNOLD, a citizen of the United States, residing at Woodridge, in the county of Bergen and State of New Jersey, have invented new and useful Improvements in Card Holders, of which the following is a specification.

This invention relates to special supports, and has for its object the provision of novel 10 means for holding a card, sign, picture, or other flat sheet like article upon a wall or other support without making any holes through the card or other article, the device being furthermore of such a nature that a 15 card of any size may be held in such a way that it may be moreover easily removed at will.

An important object is the provision of a holding means of this character which will 20 be very simple and inexpensive in manufacture, highly efficient in use, durable in service and a general improvement in the art.

With the above and other objects and advantages in view the invention consists in 25 the details of construction to be hereinafter more fully described and claimed and illustrated in the accompanying drawings, in which:

Figure 1 is a front elevation of a show 30 card mounted upon a wall by means of my device,

Figure 2 is a perspective view of one of my holding members alone,

Figure 3 is a vertical section therethrough, 35 Figure 4 is a cross section.

Figure 5 is a view of the blank from which it is formed.

Figure 6 is a face view of one of the holding members.

Referring more particularly to the drawings the letter A represents a show card, picture or other article of a flat sheet like nature which it is desired to support upon a wall or other surface. In carrying out my 45 invention I make use of four holders to be used at the corners of the card or sheet and each holder is formed from a single piece of sheet metal cut and bent to the shape illustrated though of course certain variations may be resorted to to enhance the utility of the device. I have shown each holder as consisting of a flat rectangular body portion 10 provided at one edge with an upstanding flange 11 and at an adjacent edge 50 with a reflexly bent or overhanging flange 12. The flanges 11 and 12 are at right an-

gles to each other so as to engage against adjacent edges of the card or sheet at the corner thereof. In forming the holder from a single piece of material, it is to be noted 60 that the sheet of material is in the nature of an elongated strip formed at one edge intermediate the ends thereof with a tong 13. This tong is bent back until its free edge registers with the adjacent edge of the sheet 65 and is then mashed down flat. Intermediate its ends the sheet is folded over upon the line 14 and mashed down with the free edge of this bent end arranged at a point spaced considerably from the opposite end of the 70 sheet. Prior to this bending a penetrating member is provided and mounted in place and while this penetrating member might vary in its details, it is here illustrated as being of an ordinary thumb tack 15 which 75 is pressed through the sheet and which is held in place by the folding of one end thereof as above described. Subsequent to these operations, the tong 13 is bent at right angles to the body of the device to define the 80 above described flange 11 while that portion of the sheet located between the free end thereof and the end of the folded over portion is bent at right angles and then rebent again at right angles to provide the above 85 described flange 12.

In using my devices they are simply placed upon a wall or other support at the desired points to receive the corners of the card or other sheet to be displayed and held 90 and when pressure is applied the penetrating member will be forced into the wall or other support and will operate to maintain the device firmly in place. The flanges 11 are so disposed as to engage against the side 95 edges of the card or sheet, while the flanges 12 overhang the top and bottom edges, though of course the reverse arrangement might be followed if such should be found preferable there being no restriction as to the exact manner of use. It is to be noted that a very important feature is the fact that there are no holes or anything else to deface the card, picture or the like and that the card may be easily removed from or inserted within the holders in a very simple manner.

While I have shown and described the preferred embodiment of the invention it is of course to be understood that I reserve the 110 right to make such changes in the form, construction and arrangement of parts as will

not depart from the spirit of the invention or the scope of the subjoined claims.

Having thus described my invention I claim:

5. 1. Means for holding a flat sheet against a support, comprising a plurality of members adapted to have the corners of the sheet engaged therewith, each member being formed from a single piece of resilient metal 10 bent intermediate its ends to define a main portion having one edge bent and rebent to define a flange and having an adjacent end bent over to define an overhanging flange, 30 the other portion of the sheet being bowed toward the center of the main portion and having its free end engaged beneath said overhanging flange, and a penetrating member carried by said main portion, the flat 35 sheet having its corner forced between said overhanging flange and the free end portion engaged therebeneath, the penetrating member being of a tack like nature and having its head engaged between the two portions 40 of said member.
15. 2. A device of the character described formed from a single piece of metal bent intermediate its ends to define a main portion and a spring tongue, the main portion having a flange at one edge and an overhanging flange at an adjacent edge, said tongue being bowed toward the main portion and engaged beneath the overhanging flange, and a headed fastener projecting through said 45 main portion and having its head engaged by the tongue.
20. 3. Means for holding a flat sheet against a support, comprising a plurality of members adapted to have the corners of the sheet engaged therewith, each member being formed from a single piece of resilient metal 25 bent intermediate its ends to define a main portion having one edge bent and rebent to define a flange and having an adjacent end bent over to define an overhanging flange, 30 the other portion of the sheet being bowed toward the center of the main portion and having its free end engaged beneath said overhanging flange, and a penetrating member carried by said main portion, the flat 35 sheet having its corner forced between said overhanging flange and the free end portion engaged therebeneath, the penetrating member being of a tack like nature and having its head engaged between the two portions 40 of said member.

In testimony whereof I affix my signature.

OSCAR ARNOLD.
